(57) **CLAIM**

The ornamental design for an electric power generation arrangement, as shown and described.

DESCRIPTION

FIG. 1 is a perspective view of an electric power generation arrangement showing our new design;

FIG. 2 is a right side view thereof;

FIG. 3 is a left side view thereof;

FIG. 4 is a top plan view thereof;

FIG. 5 is a bottom plan view thereof;

FIG. 6 is a front elevation view thereof;

FIG. 7 is a rear elevation view thereof;

FIG. 8 is an enlarged perspective view of the control tower portion thereof, shown separated for ease of illustration;

FIG. 9 is right side view thereof;

FIG. 10 is left side view thereof;

FIG. 11 is front elevation view thereof;

FIG. 12 is a rear elevation view thereof;

FIG. 13 is a bottom plan view thereof;

FIG. 14 is a top plan view thereof;

FIG. 15 is an enlarged perspective view of the cable duct portion thereof, shown separated for ease of illustration;

FIG. 16 is a front elevation view thereof;

FIG. 17 is a rear elevation view thereof;

FIG. 18 is a left side view thereof;

FIG. 19 is a right side view thereof;

FIG. 20 is a top plan view thereof; and,

FIG. 21 is a bottom plan view thereof.

The broken lines shown represent unclaimed subject matter and form no part of the claimed design.
